UNITED STATES PATENT OFFICE.

ELMER B. CRAFT, OF DETROIT, MICHIGAN.

PAPER-VENDING MACHINE.

Application filed October 9, 1922. Serial No. 593,257.

To all whom it may concern:

Be it known that I, ELMER B. CRAFT, a citizen of the United States of America, residing at Detroit, in the county of Wayne and State of Michigan, have invented certain new and useful Improvements in Paper-Vending Machines, of which the following is a specification, reference being had therein to the accompanying drawings.

10 This invention relates to newspaper vending machines and the invention consists in the structural features and arrangement of parts hereinafter described.

In the drawings:

15 Figure 1 is a plan view of the improved machine with its top partially broken away to show interior features;

Figure 2 is a cross section view on line 2—2 of Figure 1;

20 Figure 3 is a cross section on line 3—3 of Figure 1;

Figure 4 is a front view of an end portion of the machine;

25 Figures 5 and 6 are detail top and side views of a needle carrying arm whereby newspapers are adapted to be independently ejected from the machine.

30 In these views the reference character 1 designates a box or casing formed preferably of sheet metal and having its top 2 hinged adjacent its rear edge, as indicated at 3, to give entry to the box. The closure 2 is provided at its front edge with a depending flange 4, and is adapted to be locked 35 to the body of the box, as indicated at 5.

35 In the bottom portion of the box 1 there is arranged a sheet metal plate 6 pivoted, as indicated at 6^a, adjacent the rear wall of said box and upwardly urged by coiled 40 springs 7 respectively engaging the side edges of said plate. A supply of newspapers 6^b (or other printed matter of similar form) is adapted to be introduced into the box 1 above the plate 6, the latter sub- 45 jecting the forward portions of the stack of papers to an upward pressure tending to maintain the uppermost paper engaged with a stop plate 8 which projects rearwardly within the upper portion of the box just 50 above the discharge slot 9 in the front wall of the box. Thus as the papers are consecutively removed through said slot the spring urged plate 6 will continue to maintain the uppermost paper of the stack properly reg-

istered with said slot. In dash lines in Figure 2 there is shown the position assumed by the plate 6 when the supply of papers in the box is substantially exhausted.

55 In the upper portion of the box 1 a rock shaft 10 is mounted parallel to the front wall of the box, said shaft being journaled in bearings 11 which are preferably carried by an upward extension 11^a of the plate 8. Said shaft is sufficiently elevated within the box to be spaced a considerable 60 distance above the uppermost of the stack of papers which the box is intended to receive. Upon said shaft respectively adjacent the side walls of the box a pair of arms 12 are rigidly mounted, said arms having hinged 65 end portions 13 carrying needles 14 downwardly directed to engage the uppermost of the stack of papers. The hinged end portion of each arm is acted upon by a coiled spring 15 urging said end portion normally 70 to the initial position best shown in full lines in Figure 6. In shifting from their normal positions shown in full lines in Figure 2 to the dash line positions shown in the same 75 figure the arms 12 effect a partial ejection of the uppermost paper through the slot 9 due to engagement of the needles 14 with said paper. During the return rocking movement of the shaft 10 the pivotal ends 80 13 of the arms 12 assume the position best shown in dash line in Figure 6 so as to slide freely upon the uppermost of the stack of papers. At one end of the box 1 there is 85 formed an auxiliary compartment 16 into which an extremity of the shaft 10 is ex- 90 tended. Upon said shaft within said compartment there is mounted fast a locking plate 17 and also an actuating lever 18, the latter extending through a vertical slot 19 in the front wall of said compartment and 95 being downwardly urged by a coiled spring 19^a to establish the normal position shown in full lines in Figure 3. The plate 17 is 100 formed with a radial shoulder 20 which normally is engaged by a locking dog 21 pivoted within said compartment, as indicated at 22. 23 indicates an arm integrally projecting downward from the dog 21 for the purpose of releasing said dog from the plate 17. The arm 23 is adapted to be coin controlled as will now be described. 24 is a coin chute secured to the front wall of the 105 compartment 16 by rivets 24^a or other suit-

able means and inclining downwardly and rearwardly from a slot 25 in said wall. The rear end of the chute 24 is cut away in its upper portion, as indicated at 26, to form a seat for the lower end of the arm 23, said end and the seat therefor, being inclined to the axis of the chute 24. As will presently appear, the introduction of a proper number of coins into the chute 24 will act upon the arm 23 to effect an upward rocking of the dog 21 to disengage the latter from the locking plate 17. A receptacle 27 resting upon the bottom of the compartment 16 serves to receive the coins introduced through the chute 24. To facilitate putting papers in the box, a latch 28 is provided for engagement with the front edge of the plate 6 to hold said plate down during filling of the box, said latch being automatically released when the cover 2 is closed owing to a thrust transmitted through a rod 29.

Considering now the operation of the described invention, when it is desired to obtain a newspaper or the like from the receptacle 1, it is necessary, first, to introduce into the coin chute 24 a predetermined number of coins, such as are shown in Figure 3 at 32, the required number of coins being determined by the value of the paper. Thus when the proper number of coins have been introduced into the chute the final coin projects sufficiently to permit an application of pressure through the row of coins to the lower end of the arm 23 to raise said arm shifting the latter and the dog 21 to the positions indicated in dash lines in Figure 3. This elevation of the dog releases the same from the shoulder 20 of the plate 17 so that the operator by an upward pull upon the lever 18 may rock the shaft 8 through the angle indicated in Figure 3 between the full line and dash line positions of said lever. The free end of the dog 21 is beveled slightly upon its lower edge so that when the shaft 8 is thus rocked the plate 17 engaging the bevel of the dog 21 will effect a slight further lifting of said dog, whereby the lower end of the arm 23 will be raised entirely clear of the coins in the chute 24 permitting said coins to discharge from said chute into the receptacle 27. The described rocking movement of the shaft 8 acts, first, to embed the needles 14 in the topmost paper of the stack 6^a and then, as the arms 12 rock to their dash line positions, said paper is forwardly shifted so as to project the forward edge thereof through the slot 9. The purchaser may now grip said projecting edge and withdraw the paper from the machine. In the meantime, the lever 18 having been released, the spring 19^a will return said lever and the rock shaft to their normal positions, returning also the arms 12 to their normal rearwardly directed positions, the needle carrying ends of said

arms swinging during this return motion upon their pivots to avoid interference with such motion due to engagement with the stack of papers. As soon as the plate 17 assumes its normal position the dog 21 due to its own weight and that of the arm 23 will drop into engagement with the shoulder 20 thus lowering said arm to obstruct the coin chute and leaving the machine ready for another operation.

Owing to the small profit derived and to the probability of hard usage it is essential that a machine designed for the automatic sale of newspapers employ mechanism of simple durable and inexpensive construction and these characteristics are believed to have been achieved in the described mechanism.

An important feature of the described construction is subjection of the papers to a constant upward pressure, the stress of which pressure acts only through a relatively small area of the top-most paper so that the resistance opposing delivery of the paper through the discharge slot is slight. Thus only the front edge portion of the top-most paper engages the stop plate 8 whereby said paper is held in the proper spaced relation to the shaft 10 to be acted upon by the arm 12. The reason for failure of many devices designed for a purpose analogous to that of this invention lies in the fact that the pressure acting to maintain an end paper of the stack registered with a discharge opening has subjected said paper to too large resistance by distributing such pressure to the paper through a large area thereof.

What I claim as my invention is:

1. In a vending machine, the combination with a receptacle for articles to be sold, said receptacle having a discharge slot and having a hinged closure, of a member pivoted within said receptacle to support said articles, a spring urging said member toward the plane of said slot, a latch engageable with said member to maintain the same remote from the slot, and release means for said latch actuatable to effect release through closing of said closure.

2. In a vending machine, the combination with a receptacle for articles to be sold, said receptacle having a discharge slot and having a pivotal closure, of a member within said receptacle movable to and from the plane of said slot and forming a support for the articles to be sold, a spring urging said member toward the plane of said slot, a latch engageable with said member to hold the latter remote from said plane, a rod extending from said latch toward said closure, and a spring urging said rod toward said closure, said rod being engageable by the closure in the closed position thereof to effect release of said latch.

3. In a vending machine, the combination with a receptacle for articles to be sold, said receptacle having a discharge slot and having a hinged closure, of a member pivoted within said receptacle and acting upon the articles to urge the same toward the plane of said slot, a latch engageable with said

member to maintain the same remote from the slot, and release means for said latch actuatable to effect release through closing of 10 said closure.

In testimony whereof I affix my signature.

ELMER B. CRAFT.
